UNITED STATES PATENT OFFICE.

JACOB M. J. SCHWARZ, OF KEWANEE, ILLINOIS.

ATTACHMENT FOR PROTRACTORS.

1,408,646.

Specification of Letters Patent.

Patented Mar. 7, 1922.

Application filed April 25, 1921. Serial No. 464,067.

To all whom it may concern:

Be it known that I, JACOB M. J. SCHWARZ, a citizen of the United States, residing at Kewanee, in the county of Henry and State 5 of Illinois, have invented certain new and useful Improvements in Attachments for Protractors, of which the following is a specification, reference being had to the accompanying drawings.

10 It is the purpose of the present invention to provide a device for attachment for protractors for gauging the degree or taper of various milling cutters and the like cutting tools, and at the same time ascertain 15 whether or not the cutter or milling tool is true.

Another purpose is the provision of a device for attachment of this kind to ascertain whether or not the clearance of the 20 cutter or milling tool is perfectly uniform and true.

Still another purpose is the provision of a protractor of substantially the conventional construction shown in the drawings, comprising a head, on which a base for supporting a cutter or milling tool revolvably thereon, is mounted for sliding movement toward and from the blade of the protractor, so that the milling tool or cutter may rotate 30 relatively to the blade, for the purpose of disclosing whether or not the cutter or tool is true, and whether or not the clearance is uniform.

A further purpose is the provision of 35 means for holding the base in different adjusted positions on the head of the protractor, and means for revolvably supporting the milling tool or cutter on the base.

While the design and construction at present illustrated and set forth is deemed preferable, it is obvious that as a result of a reduction of the invention to a more practical form for commercial purposes, the invention may be susceptible of changes, and 45 the right to these changes is claimed, provided they are comprehended within the scope of what is claimed.

The invention comprises further features and combination of parts, as will be herein- 50 after set forth, shown in the drawings and claimed.

In the drawings:

Figure 1 is a perspective view of a protractor showing the improved attachment as 55 applied.

Figure 2 is a sectional view on line 2—2 of Figure 1.

Figure 3 is a sectional view on line 3—3 of Figure 1.

Figure 4 is a sectional view on line 4—4 of Figure 1.

Figure 5 is a view in elevation showing the attachment as applied to a protractor, with a different form of cutter mounted on the base of the attachment for gauging whether or not the cutting surface of the 65 tool is true, and also whether or not the clearance is uniform.

Figure 6 is a diagrammatic view showing another form of tool cutter being measured 70 or gauged.

Referring to the drawings, 1 designates the head of a protractor, and which comprises the opposed side plates and the guide flanges 3. The adjacent ends of the elongated portions 4 (which carry the flanges 3) are integrally connected, as shown at 5. The opposed plates 7 and 8 have cylindrical openings 9, which are concentrically in registration, for the reception of the dial body 10. 75 This dial body 10 has an opening 11, and upon its opposite faces are suitable graduations or degree readings 12, there being an indicator or arrow 13 for indicating the angle the head of the protractor may be set 80 with reference to the blade.

As heretofore stated the ends of the elongated portions of the head of the protractor are integrally connected, therefore a slot or passage way is caused to be formed between the elongated portions of the head. 90 The opposing plates 7 and 8 are equally spaced, substantially equal to the slot or opening or passage way between the opposed longitudinal parts of the head of the 95 protractor.

A suitable scale blade 25^a is mounted in the slot between the longitudinal portions or sides of the head, and through the opening or space between the opposed plates 7 and 8. This scale blade is provided with a longitudinally extending groove 14, and extending radially of the dial body is a screw 15, one end of which is provided with a notch 15^a, there being a lug 15^b at the extremity of the screw designed to enter the groove 14, so as to connect the screw to the blade 25^a. A portion of the blade between the groove 14 and one edge of the blade engages between the lug 15^b and the shoulder 100 110

15^a, to insure an operative connection between the blade and the screw. It will be noted that the lug 15^b is of such construction, preferably of angular shape, as to prevent the screw from turning relatively to the blade. A thumb nut 16 is threaded on the screw, and is provided with a chambered out portion 16^a, there being a spring 16^b engaged in the chambered out portion and interposed between its bottom and a flat face 16^c of the opening 11 of the dial body. It will be noted that by setting up the thumb nut 16, the lug 15^b will tighten or pull against one shoulder of the groove 14, and hold the blade 25^a in different adjusted positions relatively to the dial body. It will be noted that the dial body 10 has an annular flange 10^a which engages the shoulder 10^b of the plate 7. Diametrically opposite thumb screws 11^a of sufficient diameter to overlap the dial body are threaded into the plate 7, and act to hold the dial body in different adjusted positions relatively to the head, and thereby hold the blade 25^a in different positions relatively to the head. The spring 16^b acts to tension the lug 15^b in the groove 14 sufficiently to hold the blade 25^a in place, but it will be noted that excessive force or pressure on one end or the other of the blade will permit the blade to move. In other words the force or pressure is sufficient to overcome friction between the parts, so that the blade may be adjusted relatively to the head and vice versa. The head of the protractor may be adjusted so as to dispose the scale blade at different angles relatively to the head, particularly as the scale blade is movable with the dial body. In fact this adjustment can be made by loosening the thumb screws 11^a.

A base 19 of the general or conventional construction herein shown is mounted upon and guided by the flanges 3 of the elongated parts of the protractor head. The base has a longitudinally extending channel 20 which receives the flanges 3 of the head, whereby the base may move toward and from the scale blade. In fact the base 19 may be used, as operating in the direction toward and from the scale blade, and may be reversed if desired. The base carries a thumb screw 21, which passes through the wall of the base and binds against one of the elongated portions of the head. In fact one of the flanges 3 of the head is engaged by the shank of the thumb screw 21, for holding the base in different adjusted positions relatively to the edge of the blade.

A journal or stud 22 is mounted upon the base, and its shank 23 is threaded into the base. This journal or stud is designed to revolvably support a cutter or milling tool 24, the cutting teeth of which are to be gauged for the purpose of ascertaining whether or not the cutting teeth are true, and whether

or not there is sufficient uniform clearance. Any form of cutter or milling tool may be mounted upon the journal or stud 22, so that it may remain firmly in place and yet be permitted to rotate freely, with its cutting teeth in close proximity to the edge of the scale blade.

The base 19 is designed to be reversed, when a milling tool or cutter of considerable diameter is to be gauged. The opposing surfaces of the walls of the head may at one end thereof have inclined shoulders, which are engaged by the flat sheet metal steel plate or wedge 25, which acts to not only hold the base 19 in position, but also to prevent springing of the various parts when the thumb screw 21 is tightened. This wedge or steel plate is interposed between the inclined shoulders 26 of the opposing surfaces of the opposite walls of the head and the bottom of the channel 20 of the base. The position of the wedge or plate in this manner assists materially in holding the base 19 in position. The wedge will act to force the base in the direction of the edge of the scale blade 25^a, so as to position the teeth of the milling tool or cutter in their proper relative positions to the edge of the blade, yet not too close so as to prevent the cutter or milling tool from rotating.

When adjusting the head of the protractor, the thumb screws 11^a may be loosened, which will permit the head to rotate or move freely upon the dial body, and as the blade is connected to the dial body by means of the screw and thumb nut 15 and 16, the blade will move with the dial body and permit the head to move relatively to the blade. When the thumb screws 11^a are loosened the head may freely rotate on the dial body, so as to set the blade at different angles according to the cutter or milling tool to be gauged. After the head and the blade have been adjusted, the thumb screws 11^a may be tightened, to hold the dial body in position and the head relatively thereto. By tightening up the thumb nut 16, the scale blade 25^a is tightened relatively to the dial body, to insure moving therewith. In accomplishing this the lug 15^b pulls against one wall of the groove 14, thereby tightening the blade in the recess 27 of the dial body. In fact the edge of the blade is drawn in contact with the bottom of the recess 27 of the dial body, so that the blade will move with the body.

In order to ascertain whether or not the circumference of the cutter is perfectly true, or ascertain whether or not several cutters (to be used in gangs) are the same diameters, or whether or not they are true, and have uniform clearance, the cutter may be placed upon the journal or stud 22, the scale blade having been adjusted at 90 degree angle.

The base 19 is then adjusted toward the blade, until the longest point or part of the cutter or milling tool is disposed relatively close to the edge of the scale blade. The 5 thumb screws 11^a are then tightened, to hold the head in position, and subsequently the cutter or milling tool is revolved or rotated. As the center of the stud or journal 10 22 remains a uniform distance from the edge of the scale blade, it may be observed and determined whether or not the cutting teeth of the cutter or milling tool are true, and whether or not there is sufficient clearance for the teeth to operate. Should any 15 of the teeth of the cutter or milling tool touch the edge of the scale blade and prevent the milling tool or cutter to rotate, and should any of the teeth pass the edge of the scale blade too freely, or with consider- 20 able space between the teeth and the edge of the blade, it will disclose the fact that the cutter is untrue or uneven. In order that it may be said that the cutter or milling tool is operatively true, uniform diameter 25 and operates with sufficient clearance, the edge of each flute or cutting part of the milling tool or cutter is designed to assume a position relatively and uniformly close to the edge of the scale blade, during its arcuate 30 travel adjacent the edge of the scale blade. The same method is employed for ascertaining whether or not the cutter will have sufficient clearance, when operated. In Figure 6 it is disclosed that the cutting edges 35 of the cutter or milling tool are designed to move in a uniformly arcuate direction and relatively close to the edge of the scale blade, while the heels of the cutting edges remain at uniform distances from the edge 40 of the blade.

When it is desired to test or gauge a cutter or milling tool for spiral flutes, the cutter or milling tool may be disposed upon the stud or journal for revoluble movement, 45 in the same manner as heretofore mentioned, and in this case only a small part of the cutter or milling tool moves relatively close to the scale blade at one time. When receiving such form of cutter or milling tool 50 the entire length of the cutting edge will pass the edge of the scale blade. The same method may be followed in finding the degree of taper, or the degree of taper of any other member, with the exception that the 55 cutter is placed upon the stud or journal, then the thumb screws 11^a are loosened, the protractor head adjusted on the dial body, so that the edge of the scale blade may conform substantially to the taper of the cut- 60 ter. In cases where the cutter is of larger diameter than the cutters herein shown, or from four to five inches in diameter, the base may be reversed, thereby disposing the stud or journal a considerable distance from the edge of the blade. 65

The invention having been set forth, what is claimed as being useful is:

1. The combination with a protractor having a head and a scale blade, of a carriage adjustable upon said head and having a journal on which the cutter or milling tool may be revolubly mounted with its cutting edges relative to the edge of the scale blade, to disclose whether or not the teeth are true and uniform. 75
2. The combination with a protractor including a head and a scale blade, of a reversible carrier adjustable upon said head and having means for revolubly supporting a cutter, whereby its cutting edges may operate relatively to the edge of the blade, and the uniformity and clearance of the cutting edges may be ascertained. 80
3. In an attachment, the combination with a protractor comprising a head having guides and including a scale blade adjustable at different angles to the head, of a carrier adjustably engaging said guides and having means to revolubly support a cutter, whereby its cutting edges may be moved relatively to the scale blade, to ascertain the uniformity and clearance of the cutting edges. 85
4. The combination with a protractor including a head provided with guides and having an adjustable scale blade, of a reversible carrier adjustably engaging said guide and having means to revolubly support the cutter, whereby its cutting edges may be moved relatively to the edges of the scale blade, to ascertain the uniformity and clearance of the cutting edges. 90
5. The combination with a protractor including a head provided with guides and having an adjustable scale blade, of a reversible carrier adjustably engaging said guide and having means to revolubly support the cutter, whereby its cutting edges may be moved relatively to the edges of the scale blade, to ascertain the uniformity and clearance of the cutting edges. 95

In testimony whereof I hereunto affix my 100 signature.

JACOB M. J. SCHWARZ.
